UNITED STATES PATENT OFFICE.

JAMES COYNE, OF PITTSBURGH, PENNSYLVANIA.

BOLT AND NUT RETAINING DEVICE.

Application filed January 2, 1924. Serial No. 683,995.

To all whom it may concern:

Be it known that I, JAMES COYNE, a citizen of the United States, residing at Pittsburgh, in the county of Allegheny and State of Pennsylvania, have invented certain new and useful Improvements in Bolt and Nut Retaining Devices, of which the following is a specification.

This invention relates to bolt retainers 10 and more particularly to bolt and nut retaining devices which simultaneously prevent the rotation and falling out of the retained element.

One of the principal objects of this invention is to provide a device which is positive in action, simple, and which can be manufactured very cheaply. Another object is to provide a retaining device which can be applied to old structures as well as new 20 ones and which requires for its application the use of a small hammer only. A further object is to provide a retainer which can be constructed in such a manner as to be applied to, or removed from, bolted connections of certain types without requiring the removal of the bolt therefrom. Additional 25 features and advantages of this invention will appear from the following description viewed in connection with the accompanying 30 drawings forming part of this application, and in which various modifications of the same principle are illustrated.

In the drawings:

Fig. 1 is a side view of a retaining and locking device showing a type requiring the removal of the bolt for its application.

Fig. 2 is a top plan view of Fig. 1.

Fig. 3 is a front elevation of Fig. 1.

Fig. 4 is a side view showing a modified 40 construction which can be applied or removed without requiring the removal of the bolt.

Fig. 5 is a top view of Fig. 4, and

Fig. 6 is a front elevation thereof.

Fig. 7 is another modification showing 45 the application of a retainer to narrow constructions, where one or both members supporting the bolt are substantially of the same width as the bolt-nut.

Fig. 8 is a top view of Fig. 7, while

Fig. 9 represents a front elevation of Fig. 7.

Fig. 10 is a side view showing a simplified modification of the retainer shown in 55 Fig. 7.

Fig. 11 is a top plan view of Fig. 10 and Fig. 12 is a front elevation thereof.

Figs. 13 and 14 are respectively side and front elevations showing a modification of my invention used as a locking device to 60 prevent the unscrewing of bolt-nuts.

Fig. 15 is a combination bolt and nut locking device built along the lines of my invention.

Figs. 16 and 17 are respectively front and 65 top views of Fig. 15.

Fig. 18 is a developed view of the retainers shown in Figs. 1 to 6 inclusively.

The purpose of this application for Letters Patent is to cover different means of 70 securing bolts and nuts in their places than the ones shown in Patent Number 1,473,177, dated November 6th, 1923 and issued to myself; which patent covered combination bolt and nut retainers having substantially the 75 shape of an S, to be applied more particularly to forked hinged connections found so frequently in car brake connections.

Although the retaining means forming 80 the subject of this application may be readily used on forked hinged connections, it will be easily understood that, owing to their simpler shape, they may be put in use in a great variety of installations where the S shaped retainers would not answer as well. 85 Moreover, by using the former retainers, one for the bolt-head and one for the nut, the retention of either part is practically assured.

Reference being had to Figs. 1, 2, 3 and 90 18, my retainer comprises a blank strip of soft and pliable metal 1 of suitable size and thickness to be easily folded by hand or with the assistance of a small hammer over the bolt head or nut to be retained. Adjacent 95 the forward end 2 of said strip are punched out the oblong apertures 3 which are to be engaged by the tip ends 4 of the fingers 5 provided on the rear end of the blank strip. The inner sides of these fingers are spaced 100 apart to embrace the sides of the bolt head or nut which is to be retained and part of the metal between that space is formed into a tongue 6 which is to be folded over the bolt head, thus preventing the latter from 105 falling out. Suitably positioned in the blank strip is the aperture 7 through which the bolt-stud is passed prior to folding the strip. This construction would, of course, require the removal of the bolt-stud in order 110

to apply the retainer. The latter can, however, be modified in the manner shown in Figs. 4 to 6 to enable its application without extracting the bolt. This modification consists in providing in the body of the strip an open slot 8 (shown in dot and dash lines in Fig. 18) instead of the closed aperture 7.

This retainer is applied on the bolt to be retained while in its flattened, or blank state, and is then folded by hand or by means of a small hammer over the sides of the structural member 9, the bolt head 10 and the tips of the fingers are inserted in the holes 3 after which the former are bent either up or down to hold them fixedly in place. Owing to the thinness of the retainer, it is usually found preferable to form in the fingers the arcuate portions 11, as an additional guaranty against the rotation of the bolt. The tongue 6 is then folded over the head, thereby locking the bolt against rotation as well as preventing its accidental escape.

In Figs. 7 to 12 inclusive are illustrated two types of retainers intended especially for small constructions, as already stated. It will be noted therein that the tongue member 6, in Figs. 1 to 6, has been eliminated, the body proper of the retainer having been folded over the bolt or nut. The retainer with the two fingers 12 may be used preferably for securing bolt-nuts, as the portion of the bolt-stud 13, usually extending above the nut, is taken care of by the space 14 between the fingers. When the retainer is to be used to hold the bolt proper, the construction with the single finger 15 may be used. This construction enables the retainer to be applied more rapidly and permits a more liberal dimensioning of the single central finger. The method of applying this modified construction is substantially the same as the one already described, and need therefore not be repeated here.

Retainers of the type shown in Figs. 13 and 14 are slight modifications of those shown in Figs. 1 to 6; the modification consisting in the elimination of the tongue 6, to make the retainers more suitable for use in connection with bolt-nuts, having protruding bolt-studs.

In Figs. 15 to 17 is shown a combined bolt and nut locking device incorporating in its upper part the nut locking device shown in Figs. 13 and 14, whereas the lower part is slightly modified to provide means for locking the bolt proper against rotation. As shown, a depending tongue 16 is stamped out

of either side of the retainer to be folded over, or against one side of, the bolt-head, to prevent it from turning. Since both, the nut and bolt, are locked against rotation, it is apparent that neither part can work loose, thus insuring a permanent connection for the structural members 17 and 18 held by said bolt.

If desired, the tongue 16 could be made long enough to permit it being folded over the bolt-head, thus simultaneously preventing the latter from turning and falling out of place in case of rupture of the bolt-stud or accidental loss of the bolt-nut.

Many changes in the precise construction and form of my retainers may be made without exceeding the scope of the claims and I reserve myself the liberty of making all such changes as may be thought desirable.

I claim:

1. In combination with a structural member, a bolt inserted therethrough; a bolt and nut locking means to simultaneously prevent the rotation and accidental disengagement of said bolt and nut; said locking means comprising a unitary strip of pliable material adapted to surround said structural member and having an aperture to be engaged by said bolt; one end of said strip having a pair of pliable parallel fingers spaced to engage opposite sides of said nut and having arcuate portions formed therein adapted to prevent the rotation of said nut; the other end of said strip having provided therein apertures to be engaged by said fingers when in folded position.

2. In combination with a structural member, a bolt inserted therethrough; a bolt and nut locking means to simultaneously prevent the rotation and accidental disengagement of said bolt and nut; said locking means comprising a unitary strip of pliable material adapted to surround said structural member and having an aperture to be engaged by said bolt; one end of said strip having a pair of pliable parallel fingers spaced to engage opposite sides of said nut and having arcuate portions formed therein adapted to prevent the rotation of said nut; the other end of said strip having provided therein apertures to be engaged by said fingers when in folded position, and a pliable tongue formed integrally with said strip and positioned intermediate said fingers to prevent the accidental removal and rotation of said nut.

In testimony whereof I affix my signature.
JAMES COYNE.
